UNITED STATES PATENT OFFICE.

THOMAS BROWN, OF LONDON, ENGLAND.

SHIP'S RIDING-BITT.

Specification of Letters Patent No. 12,620, dated April 3, 1855.

To all whom it may concern:

Be it known that I, THOMAS BROWN, a subject of Great Britain, residing at No. 113 Fenchurch street, in the city of London, 5 have invented a new and useful Improvement in Sailing and other Vessels Produced by a New Form and Arrangement of the Riding-Bitts; and I do hereby declare that the following is a full and exact description 10 thereof, reference being had to the accompanying drawings, making a part of this specification, Figure 1 being a top view of a section of a deck of a vessel with one of my improved riding-bitts combined therewith; Fig. 2, a vertical section in the line *a a* of Fig. 1; Fig. 3, a vertical section in the line *b b* of Fig. 1, and Fig. 4 a vertical section in the line *x x* of Fig. 1 and exhibiting a front elevation of my improved 15 riding-bitt.

Similar letters indicate like parts in all the figures.

A vessel's riding-bitts have heretofore been made of strong wooden shafts, or 20 beams, which pass through the deck and have their lower ends secured to the deck below; the portions of said shafts which rise above the deck, and form the riding-bitts, being protected by metallic casings.

25 The following disadvantages attend the use of the aforesaid form and arrangement of riding-bitts, viz: First, the very great strain exerted by the cable upon the said bitts, as it is drawn around them, renders it impossible to prevent their descending 30 shafts from working in the deck, and consequently producing leaky joints between them and the deck, and, second, the descending shafts of the said riding bitts, take up 35 much valuable space between decks.

40 My improvement in riding-bitts, consists in making them of metallic tubes *c, c*, which have sufficiently broad flanges *d, d*, at their lower ends to enable them to rest firmly

upon the deck; the said tubes being secured 45 over openings *f*, in the deck, by means of a suitable number of bolts *g, g*, passing through their flanges into, (or secured to plates passing beneath,) the deck beams *h, h*, and by lugs *e, e*, which descend from the 50 under side of the said flanges into recesses formed in the deck.

The advantages arising from the use of my improved form and arrangement of a vessel's riding-bitts are as follows, viz: 55 first, the openings *f*, in the deck—within and below the inner diameter of the bitts—allow light and air to pass through the deck to the space between decks in fair weather and in foul weather; the covers *j*, which are 60 then placed over the tops of the bitts, may have thick pieces of glass inserted in them, for the purpose of allowing light to pass below at all times; second, the joint between the base of the bitts and the deck, can be 65 made perfectly water tight. And third—much valuable space is saved between decks, by securing the bitts entirely to a single deck.

70 The norms *k, k*, may be combined with the riding bitts in the manner represented in the drawings, or in any other that may be deemed expedient.

75 What I claim as my invention and desire to secure by Letters Patent, is—

The tubular metallic riding bitts, when entirely secured to a single deck of a vessel and arranged substantially in the manner and for the purpose herein set forth.

80 In witness that the above is a true specification of my hollow metal self supported ventilating riding bitt I do hereby subscribe my name in presence of witnesses.

THOMAS BROWN.
